THERMAL-RESPONSIVE DEVICE

Gustave F. Bahr, Bridgeport, Conn., assignor to
 Casco Products Corporation, Bridgeport, Conn.,
 a corporation of Connecticut

Application March 19, 1940, Serial No. 324,763

17 Claims. (Cl. 200—142)

This invention relates to thermal-responsive devices, and, more particularly, to one which is adapted to be thermally and electrically connected to a heating element of an electrically heated appliance for controlling the circuit thereto in response to overheating of the heating element and current changes of the supply circuit.

The device of the present invention is particularly adapted for use with automatically controlled cigar lighters of the type disclosed in my copending application, Serial No. 138,133, filed April 21, 1937, but the invention, in its broader aspects, is not limited to such a use.

It is an object of the present invention to provide a device which will permanently open the supply circuit if the heating element of the appliance should attain some dangerous heat or if a short circuit should occur such as to cause a dangerous heat to develop due to the resistance of any part of the circuit.

Thermal-responsive devices of the type disclosed by the present invention have generally included a fusible element, fusible within a range of temperatures above which it was not desired to have the device attain. The fusible elements heretofore proposed have generally been formed of wax or wax-like compositions or fusible metallic materials having a fusing or melting temperature below some predetermined one. The wax or wax-like compositions, of which many of the heretofore proposed fusible elements have been formed, were found not to be satisfactory under many conditions of use, for the reason that the wax or wax-like compositions would soften under prolonged heating at a temperature somewhat below that of their melting temperature and be no longer effective to perform its function in the device.

The metallic materials, although many were not affected by the prolonged temperatures substantially that of their fusing temperatures, nevertheless, have been difficult to use in devices controlling electric circuits, for the metallic materials oftentimes after they had fused or melted would come into contact and bridge spaced members forming a part of the circuit controlled and would again complete the circuit or short circuit the same.

The device of the present invention obviates the difficulties to be found in the previously proposed devices, for the fusible element of the present invention comprises a flat wafer-like mass of nonconducting composition having a definite known melting temperature housed within a casing formed of current-conducting material.

The fusible element of the present invention preferably is formed of a material having a melting temperature below the temperature above which it is not desired to have the device attain.

The element should be formed of material which is not affected when subjected to prolonged temperatures somewhat below its melting temperature and sulphur, as disclosed in the Russell D. Conboy application, Serial No. 322,698, filed March 7, 1940, serves admirably as the fusible material but other materials having similar properties may be used. The casing housing the wafer-like mass of material, as it is current conducting, may be disposed so as to form a part of the circuit controlled and will, therefore, be effective to control the circuit through cooperation with other elements of the device, the mechanical movement of which the fusible element controls.

The device of the present invention also as it is to be connected to the appliance or the like with the fusible element in heat-receiving relation with the heating element will also be effective to control the circuit to the heating element should the latter attain a dangerous heat such as may occur if the supply circuit is allowed to remain closed for an undue length of time.

My device comprises, in its now preferred form, a pair of spaced contacts with a movable contact tending to be urged by a spring to a position intermediate the spaced contacts and out of engagement therewith, but which normally is held in good electrical engagement with one of said spaced contacts by my fusible element which is engaged by the other of said spaced contacts. The melting or fusing of the element allows the spring to urge said movable contact to the position intermediate the spaced contacts and out of engagement with the contact against which it had been held by the fusible element.

By forming the fusible element of a flat wafer-like mass of fusible material, the device may be made relatively small so that it occupies very little space when assembled and mounted to the appliance.

In one form of the invention, the fusible element is accessible through a removable closure forming a part of the casing housing my device. This permits the fusible element to be easily replaced without necessitating the removal of the device from the appliance.

Other features and advantages will herein-after appear.

In the accompanying drawing:

Figure 1 is a sectional view of my device.

Fig. 2 is a view similar to Fig. 1, but showing a modified form of my device and illustrating the position of the circuit-breaking members after the fusible element has melted.

Fig. 3 is an exploded view showing the various elements of my device.

Fig. 4 is a plan view of my fusible element.

The device of the present invention, referring now to Fig. 1, comprises a metallic sleeve 10

having a plurality of fingers 11 bent inwardly thereof. A disk 12 of insulating material, carrying a metallic stud 13, seats against the inner faces of the fingers 11 and closes the one end of the sleeve 10. The stud 13 projects beyond the inner face of the disk 12 and the projecting portion is riveted over to form a head 14 which clamps the disk 12 against a shoulder 15 on the stud 13.

A coil spring 16, seating on the disk 12, urges a metallic disk 17 to the left, as viewed in Fig. 1, and away from the head 14. The disk 17 is provided with a central concave portion forming a contact surface 17a projecting toward the head 14 and receiving a cup-like member 18 held therein by any suitable means, but herein shown as having a friction fit within the concavity. The cup-like member may be of any suitable shape desired, but, as herein shown, the cup-like member, when assembled with the disk, forms a frusto-conical plug projecting from the one face of the disk 17. The disk 17 has its peripheral edge bent back to provide a flange 20 forming a guide surface slidably engaging a band 21 of insulating material fitted within the shell 10 and forming an insulated lining for the same. The other end of the shell 10 is closed by a disk 22 of insulating material received within the end of the shell 10 and held against the edge of the band 21 by a flanged ring 24 threadedly mounted to the shell 10. The disk 22 carries a centrally located stud 23 provided at the inner end thereof with a spider member having a plurality of resilient fingers 25. The spider is secured to the inner face of the disk 22 by hitting over the end of the stud 23 to form a retaining head 26.

The stud 23 is provided with an integral stop collar 27 which engages the outer face of the disk 22 and cooperates with the head 26 of the stud to hold the disk 22 and spider against relative movement. The outer end of the stud 23 is threaded to take a nut or other securing device to clamp a contact clip, not shown, against the collar 27.

The spring 16, as will be seen, will urge the disk 17 to the left, as viewed in Fig. 1, and out of engagement with the head 14 of the stud 13 which is internally threaded to permit its thermal and electrical attachment to the heating element of the appliance to which the device is to be used. To hold the disk 17 in engagement with the head 14 against the action of the spring 16, I employ a fusible element which comprises a flat wafer-like mass 28 of non-conducting material meltable at a temperature below the temperature above which it is not desired that the device attain.

The wafer 28 is housed within a suitable casing 29 of some current-conducting material such as brass or the like. The fusible element is disposed between the resilient fingers 25 of the spider member and the substantially conical plug formed by the cup-like member 18 and is held against the plug by the resilient fingers 25. The resiliency of the fingers 25 is sufficient to hold the element in good electrical engagement with the substantially conical nose of the plug and to urge the contact surface 17a against the head 14. The element is provided on the face engaged by the nose of the plug with a plurality of fingers 30 projecting centrally of the same, but terminating just short of the center thereof. The fingers 30 preferably are

formed, as clearly shown in Fig. 4, by stamping from the one face of the casing a substantially cruciform portion.

It will be seen that when the stud 13 is thermally and electrically conducted to the heating element, not shown, and the stud 23 is connected to the opposite side of the supply circuit, the circuit through the device will include the stud 13, head 14, contact surface 17a, the plug 18, the conducting casing 29, fingers 25 and stud 23.

As the casing 29 of the fusible element forms a part of the circuit, a surge of current will cause the casing to become overheated due to the resistance offered. If the casing attains a temperature greater than the melting temperature of the fusible material, the same will melt or fuse and be no longer effective to support the fingers 30 against the spring urged plug 18. The coil spring 16 acting against the disk 17 carrying the plug 18 will cause the latter to partially pierce the fusible element, and this movement of the disk will cause a displacement of the head 14 and the contact surface 17a to break the circuit at the point of engagement between the head 14 and the contact surface 17a.

If the supply circuit should be held closed for an undue length of time, the likelihood of a dangerous condition arising, due to overheating of the element, will be completely obviated by the present invention. It will be seen, therefore, that if the heating element should attain some dangerous degree of heat, the stud 13 will conduct this heat to the metallic disk 17, plug 18, which, as previously explained, is in contact with the one face of the fusible element. The heat so conducted, if of a temperature higher than the melting temperature of the fusible material, will cause the same to fuse or melt and the nose of the plug 18 again will be urged into the element as just above explained to break the electrical engagement of the contact surface 17a and the head 14.

It will, therefore, be seen that the present device may be used to control the supply circuit of a heating element and will guard against the likelihood of a dangerous condition arising, due, either to a dangerous change of the current of the supply circuit or by the supply circuit being held closed for a time sufficient to cause the heating element to attain a dangerous temperature.

The melting or fusing of the material 28, as it has no current-conducting properties, will not give rise to the condition which has arisen in some of the previously proposed devices of a similar nature, wherein the fusible material was itself current-conducting and caused a short circuit if, in fusing, it bridged spaced components of the circuit controlled.

In the form of the invention shown in Fig. 1, the fusible element, if destroyed, may be quickly replaced by a similar fresh one by merely removing the conductor, not shown, from the stud 23 and unscrewing the ring 24 which will permit the disk 22, carrying the stud 23 and spider member, to be removed rendering the destroyed cartridge accessible for removal and substitution of a new one.

In the form of the invention shown in Fig. 2, the device is substantially identical with that shown in Fig. 1 with the exception of the flanged ring 24 employed in the form of the invention shown in Fig. 1 to hold the parts in assembled relation. In the form of the invention illus-

trated in Fig. 2, the flanged ring 24 has been dispensed with and the shell 18 is provided with a plurality of fingers 32 at its end opposite to the fingers 11 to hold the parts once assembled in that relation. The elimination of the flanged ring 24 does not permit a destroyed element to be readily replaced by a fresh one, and, in this form of the invention, it is intended, once the element is destroyed, to replace the device having a destroyed element with an entirely new device. 10

Variations and modifications may be made within the scope of the invention and portions of the improvements may be used without others.

I claim:

1. In a device of the type described, a pair of spaced contacts; a movable contact; resilient means tending to dispose said movable contact intermediate said spaced contacts and out of engagement therewith; and a fusible member in contact with one of said spaced contacts and interposed between the same and the movable contact, said fusible member comprising a quantity of fusible nonconducting material held within a housing of conducting material and holding said movable contact in engagement with the other of said spaced contacts. 15

2. In a device of the type described, a pair of spaced contacts, one of said contacts being resilient; a movable contact; resilient means tending to hold said movable contact intermediate said spaced contacts and out of engagement therewith; and a fusible member engaged by said resilient contact and holding said movable contact in engagement with the other of said spaced contacts, said fusible member comprising a quantity of fusible nonconducting material held within a housing of conducting material. 20

3. In a device of the type described, a pair of spaced contacts, one of said contacts being resilient; a movable contact; resilient means tending to hold said movable contact intermediate said spaced contacts and out of engagement therewith; and a fusible member being engaged by said resilient contact and holding said movable contact in engagement with the other of said spaced contacts, said fusible member comprising a flat wafer-like mass of nonconducting material held within a housing of conducting material. 25

4. In a device of the type described, a casing having a pair of opposite walls; a contact carried by each wall; a movable contact within the casing; a spring seated on one wall of the casing urging said movable contact to a position intermediate said first-named contacts and out of engagement therewith; and a fusible member engaged by the contact carried by the wall opposite the wall seating said spring, said fusible member comprising a quantity of nonconducting material having a predetermined melting point held within a housing of conducting material and holding said movable contact in engagement with the other of said spaced contacts against the action of said spring. 30

5. In a device of the type described, a pair of spaced contacts; a movable contact; resilient means tending to dispose said movable contact intermediate said spaced contacts and out of engagement therewith a fusible member in contact with one of said spaced contacts, said fusible member comprising a quantity of fusible nonconducting material held within a housing of conducting material and holding said movable contact in engagement with the other of said spaced contacts; and means for connecting the 35

last-named contact in current and heat-conducting relation to a heating element of an electrically heated appliance.

6. In a thermal control device for an electrically heated device, a pair of spaced contacts; a movable contact; resilient means tending to dispose said movable contact intermediate said spaced contacts and out of engagement therewith; a fusible member in contact with one of said spaced contacts, said fusible member comprising a quantity of nonconducting material melttable at a predetermined temperature held within a housing of current-conducting material and holding said movable contact into engagement with the other of said spaced contacts; and mounting means for said device for electrically connecting the same to said heating element and providing a direct heat path between the heating element and the fusible member. 40

7. In a device of the type described, a pair of spaced contacts; one of said contacts being resilient; a movable contact; resilient means tending to dispose said movable contact intermediate said spaced contacts and out of engagement therewith; and a fusible member engaged by said resilient contact and holding said movable contact in engagement with the other of said spaced contacts, said movable contact comprising a plug having the end thereof engaged by said fusible member of substantially conical shape, said fusible member comprising a quantity of nonconducting material melttable at a predetermined temperature held within a pierceable housing of conducting material, the melting of said nonconducting material allowing said resilient means to cause said plug to pierce said housing and be urged out of engagement with the spaced contact. 45

8. In a device of the type described, a pair of spaced contacts; a movable contact; resilient means tending to dispose said movable contact intermediate said spaced contacts and out of engagement therewith; a fusible member in contact with one of said spaced contacts, said fusible member comprising a quantity of fusible nonconducting material held within a housing of conducting material and holding said movable contact in engagement with the other of said spaced contacts, the last-named contact including means for thermally and electrically connecting the device to a heating element of an electrically heated appliance, whereby said fusible member is subject to the heat of the heating element and heat caused by current changes of the supply circuit. 50

9. In a device of the type described, comprising an open ended casing; a pair of transverse walls of insulating material closing said ends; a contact carried by each of said walls; a movable contact; resilient means tending to urge said movable contact to a position intermediate said spaced contacts and out of engagement therewith; a fusible member engaged by one of said spaced contacts, said fusible member holding said movable contact in engagement with the other of said spaced contact and comprising a quantity of fusible nonconducting material held within a housing of conducting material; and a lining of insulating material insulating said contacts and fusible member from said casing. 55

10. In a device of the type described, a pair of spaced contacts; means for bridging said contacts comprising a movable contact normally disposed intermediate said spaced contacts and

out of engagement therewith, and a fusible member in contact with one of said spaced contacts and holding said movable contact in engagement with the other of said spaced contacts, said fusible member comprising a quantity of fusible nonconducting material held within a housing of conducting material; and means for mounting said device to a heating element of an electrically heated appliance, said mounting means forming with said movable contact a direct heat path between the heating element and the fusible member.

11. In a device of the type described, an open ended casing; a pair of transverse walls of insulating material closing said ends; a contact carried by each of said walls, one of said contacts comprising a plurality of resilient fingers projecting toward the opposite wall; a movable contact; resilient means tending to urge said movable contact to a position intermediate the contacts carried by said walls and out of engagement therewith; and a fusible member engaged by said resilient fingers and urged thereby into engagement with said movable contact, the resiliency of said fingers being sufficient to hold said movable contact in engagement with the other of said spaced contacts, the resilient means causing the movable contact to pierce said fusible member upon the fusing of the same whereby the movable contact is moved out of engagement with said spaced contact.

12. In a device of the type described, an open ended casing; a pair of transverse walls of insulating material closing said ends; a contact carried by each of said walls; an intermediate transverse wall; a plug carried by said intermediate wall; resilient means seating on one of said first-named walls urging said intermediate wall out of engagement with the contact carried by the wall upon which said resilient means is seated; and a fusible member disposed between the other of said spaced contacts and the plug carried by said intermediate wall for holding said wall in electrical engagement with the other of said spaced contacts, said fusible member comprising a quantity of fusible nonconducting material held within a housing of conducting material.

13. In a device of the type described, a casing having a pair of opposite end closing walls; a contact carried by each wall; a movable contact within the casing; a spring seated on one wall of the casing urging said movable contact to a position intermediate said first-named contacts and out of engagement therewith; a fusible member engaged by the contact carried by the wall opposite the wall seating said spring, said fusible member comprising a quantity of nonconducting material having a predetermined melting point held within a housing of conducting material and holding said movable contact in engagement with the other of said spaced contacts against the action of said spring; and means removably secured to the casing for permitting access and removal of the wall carrying the contact engaged by the fusible member to permit a destroyed fusible member to be substituted with a fresh one.

14. In a device of the type described, an open ended casing; a pair of transverse walls of insulating material closing said ends; a contact

carried by each of said walls; a current-conducting intermediate transverse wall; a plug of current-conducting material carried by said intermediate wall; resilient means seating on one of said first-named walls urging said intermediate wall out of engagement with the contact carried by the wall upon which said resilient means is seated; a fusible member disposed between the other of said spaced contacts and the plug carried by said intermediate wall for holding said wall in electrical engagement with the other of said spaced contacts, said fusible member comprising a quantity of fusible nonconducting material held within a housing of conducting material; and means for insulating said intermediate wall and the plug carried thereby from said casing.

15. In a device of the type described, a casing having a transverse wall of insulating material closing one end thereof; a removable transverse wall of insulating material closing the opposite end of said casing; a contact carried by each of said walls; a movable contact within the casing; resilient means tending to urge said movable contact to a position intermediate said wall contacts and out of engagement therewith; and a fusible member engaged by the contact carried by said removable wall holding said movable contact in engagement with the other of said wall contacts and comprising a quantity of fusible nonconducting material held within a housing of conducting material.

16. In a device of the type described, a pair of spaced contacts; a movable contact; resilient means tending to hold said movable contact intermediate said spaced contacts and out of engagement therewith; and a fusible member in contact with one of said spaced contacts, said fusible member comprising a quantity of fusible material held within a thin walled housing of conducting material and holding said movable contact in engagement with the other of said spaced contacts, the fusible material reinforcing said housing and holding the same against collapse under the urging of said resilient means, the fusing of said material allowing said resilient means to collapse said housing whereupon the resilient means urges said movable contact out of engagement with the other of said spaced contacts.

17. In a device of the type described, a pair of spaced contacts; a movable contact; resilient means tending to hold said movable contact intermediate said spaced contacts and out of engagement therewith; and a fusible member in contact with one of said spaced contacts, said fusible member comprising a quantity of fusible material held within a thin walled housing of conducting material and holding said movable contact in engagement with the other of said spaced contacts, the wall of said housing engaged by said movable contact being collapsible, the fusible material reinforcing said wall and holding the same against collapse under the urging of said resilient means, the fusing of said material allowing said resilient means to collapse said wall whereupon the resilient means urges said movable contact into said housing and out of engagement with the other of said spaced contacts.

GUSTAVE F. BAHR.
